UNITED STATES PATENT OFFICE.

JAMES WILKINSON, OF BIRMINGHAM, ALABAMA, ASSIGNOR, BY DIRECT AND MESNE ASSIGNMENTS, TO THE WILKINSON STEAM TURBINE COMPANY, A CORPORATION OF ALABAMA.

GOVERNING MECHANISM FOR TURBINES.

SPECIFICATION forming part of Letters Patent No. 751,888, dated February 9, 1904.

Application filed April 7, 1903. Serial No. 151,504. (No model.)

To all whom it may concern:

Be it known that I, JAMES WILKINSON, a citizen of the United States, residing at Birmingham, in the county of Jefferson and State of Alabama, have invented certain new and useful Improvements in Governing Mechanism for Elastic-Fluid Turbines, of which the following is a specification.

My invention relates to governing mechanism for elastic-fluid turbines wherein electromagnetic means controlled by a governing device sensitive to the speed of rotation of the turbine-shaft are employed to regulate admission of fluid-pressure to expansion-nozzles, in which it is converted largely into velocity before delivery against the vanes on the rotor-shaft.

In a pending application I have shown and described various means for effecting the regulation of turbines by oscillating one or more of the valves controlling the admission of pressure to the nozzles, so that it was delivered to the rotor in pulsations or blasts which varied in duration according to the load.

It is the object of my present invention to incorporate this oscillatory regulation into an improved governing mechanism especially adapted to control high-power turbines employing large numbers of nozzles and operating under loads that may vary materially.

In carrying out my invention I use a speed-governor-controlled collar or commutator provided with separate circular contact-plates and interposed bands of insulation, which is engaged by brushes connected to wires controlling the valve-motors either singly or in groups.

It is a further object of my invention to provide an improved semirotary valve located in the throat of each nozzle and forming when in its open position a part or the whole thereof and to perfect the electromagnetic operating means for the valves. I also contemplate using a complete circular row of nozzles around the turbine to obtain the full power of the rotor-wheel and have adapted the governor to control them separately or in oppo-

sitely-disposed groups of any desired number of nozzles.

In the accompanying drawings, illustrating my invention and forming a part hereof, Figure 1 is a vertical sectional view of the turbine, showing the governing mechanism in elevation. Fig. 1^a is a diagrammatic view of a generator with its terminals suitably grounded. Fig. 2 shows the turbine in plan with the governor broken away and shown in elevation and the valve-motors coupled up in pairs. Fig. 3 is a detail view of a modified form of the governor collar or commutator. Fig. 4 is an enlarged sectional view of the valve and its mounting in the turbine-shell shown in Fig. 1 with the motor shown in elevation. Fig. 5 is a side view of Fig. 4, partly broken away along the line *x* *x* of said figure, showing the nozzles and rotor-vanes in section and the semirotary valves in open and closed positions. Fig. 6 is an end view of the valve-armature commutator through the line *y* *y* of Fig. 4, showing the electrical connections with an illustrative governor action, the valve being in its closed position. Fig. 7 is the same as Fig. 6, showing the position of the parts when the valve is in its open position. Fig. 7^a is a transverse section through *z* *z* of Fig. 4, showing the construction of the motor-armature. Fig. 9 is a detail view of the valve removed, showing in connection therewith its motor-armature and commutator. Fig. 10 shows a modified or segmental valve. Fig. 11 is a diagrammatic view illustrating the action of a valve throughout the range of travel of the governor-collar.

The same reference-numerals refer to similar parts throughout the drawings.

The rotor or wheel 1, with two rows of peripheral concavo-convex vanes 2, is rigidly fixed to the main shaft 3, which has suitable bearings in the turbine-frame, in which it is vertically mounted. The turbine-casing 4 has arranged around its upper periphery an annular chamber 5, provided with inlet-ports 6 for the admission of elastic fluid, which is delivered at an acute angle against the vanes 2 through a complete circular row of expansion

passages or nozzles 7, each of increasing area toward its discharge end and angularly disposed to the rotor. A row of stationary guides or intermediates 2^a on the inner wall of the 5 casing 4 and disposed between the rows of vanes 2 on the rotor serves to direct the passage of elastic fluid through said vanes to an annular chamber 8, from which it is exhausted through the ports 9 either to open air or to a 10 condenser.

The general construction and operation of the turbine as just described is of the usual character, and may therefore be varied without affecting my present invention, which relates to the governing and regulating mechanism. 15

I provide each of the nozzles 7 with a rotary valve 10, cylindrical in cross-section and having an elongated flaring opening 11 disposed 20 centrally and longitudinally thereof, through which the elastic fluid is admitted to the expansion-passages from the chamber 5. Each valve is located in the throat or reduced portion 12 of its respective nozzle between the 25 frames 13 and provided with suitable bearings 14 and stuffing-boxes 15 at either end, as more clearly shown in Fig. 4. The valve-opening 11 flares upwardly or toward the chamber 5, having its side walls convexly curved, so that 30 when in an open position they correspond with the curve of the nozzle-frames 13 and present an uninterrupted passage for the elastic fluid. By locating a valve of this construction in the reduced portion of the nozzle it forms a part or, 35 if desired, the whole of the throat when in its open position, thus providing a ready means for repairing or replacing the throat independently of the nozzle-frames. At the same time it avoids the friction and reduction of pressure 40 resulting from the use of valves interposed in the steam-chamber and operating in front of the nozzle. In its open position the valve is balanced independently of the pressure, by reason of its forming a portion of the 45 throat; but when closed it is no longer balanced, the excess of pressure above the valve serving the advantageous purpose of holding it securely against its seat. If desired, the valve 50 may be segmental, so that it forms but one side 55 of the throat when open; but in either construction, its motion being rotary and covering an angle less than forty-five degrees, little power will be required to operate it. The valve-stem 16 extends outwardly from the casing 60 and through a coupling 17 is detachably connected with the shaft of a valve-operating motor 18. These motors are supplied with electric potential by a generator G, whose positive main-leads to a special conductor, which may 65 be a metallic ground P, while the negative main leads to an earth-ground N. The motor-armature 19 is keyed to the shaft 20, suitably mounted in bearings at each end of the motor-frame and connected through 17 to 65 the valve-stem 16. The armature has poles

21 and 22, whose outer surfaces are curved in the arc of a circle struck from the center of shaft 20, corresponding with which are the reversely-curved pole-pieces 23 and 24 of the field, suitably secured to the motor-casing. 70 The armature-coils 25 are wound lengthwise between the poles and connected at one end to segments 26 and 27 and at the other to segments 28 and 29 of the motor-commutator 30. A differentially-wound resistance-coil 31 is interposed among the armature-coils, connecting them at their middle with plate 32 of the commutator located between segments 27 and 29, from which it is suitably insulated. Segments of insulation 33 and 34 are interposed 80 between segments 26 29 and 27 28. The field-coils 35 are connected to the conductor P and to a brush 36, which engages commutator 30 and is arranged to contact with segments 27, 32, and 29 in turn as the valve oscillates. A 85 brush 37, which contacts with segment 26 when the valve is closed, is connected by wire 38 with a brush 39, engaging the governor-commutator 40. A brush 41 contacts with segment 28 when the valve is open and is connected by wire 42 with a brush 43, engaging commutator 40, which carries a spirally-tapered contact-plate 44, suitably connected with the generator through wire 45 to ground N. 90

Referring now to Fig. 6 and assuming the 95 generator to have the proper difference of potential at its terminals, this difference will exist in the apparatus as follows: The sleeve 44 will be charged from the N side and the brush 39 from the P side through the field 35, brush 36, segment 29, coil 25, segment 26, brush 37, and wire 38, when the valve will be closed. If then during the rotation of the commutator 40 the brush 39 makes contact with plate 44, an electric current will be established in 100 the coils 35 and 25, which will so magnetize the armature-poles with regard to the field that the armature will be caused to rotate in the valve-opening direction. The full strength of the current is used to start the rotation of the armature, and the torque is increased by 105 reason of the curved structure of the field and armature poles, which permits a close and extended influence throughout the magnetic field. Though the full current is used to start 110 the rotation, it is my intention to reduce the arc of discharge when the current is broken and save current by cutting out half of the armature-coils from the circuit and at the same time interposing a resistance 31 as soon as the 115 armature movement is well under way. Thus as the commutator 30 rotates from its position in Fig. 6 to that of Fig. 7 the segment 29 passes from under brush 36, which then engages segment 32. This segment is connected to the middle of the armature-coils through the differentially-wound resistance 31, sufficient to greatly 120 reduce the current flowing through the coils 25 and 35, so that when the circuit is broken by the segment 26 passing from under the brush 37 125 130

the arc of discharge will be small. The brush 36 is so placed with regard to brush 37 that the latter leaves segment 26 before segment 27 reaches the former, whereby all current is 5 cut off from the motor and the remaining portion of the armature movement accomplished by its momentum assisted by the eccentric bearing 46 on the commutator 30, provided with two stop-shoulders 47 and 48, which engage 10 a shoe 49, carried by a spring-arm 50, bolted to the motor-frame, which shoe rides on said eccentric bearing and serves to limit the armature's movement either way and hold it in position between reversals.

15 Referring to Fig. 7, which shows the armature reversed and the valve open, brush 36 is in contact with segment 27, brush 41 with segment 28, wire 38 open-circuited, and wire 42 alive to the brush 43, so that upon the latter's 20 contact with plate 44 the coils 25 and 35 will be energized and their cores polarized in relatively reversed directions, so that the armature movement will thus be reversed and the valve closed. Current is entirely cut off during 25 the periods of the valve's inactivity, and since the resistance is interposed almost immediately after the armature-coils have been energized the motor will operate with a minimum amount of current. The motor-frames 30 are secured to brackets 51, extending outwardly from the turbine, by bolts 52, which pass through elongated slots 53, which provide for a rocking adjustment.

I regulate the number of passive nozzles 35 maintained open or closed and the oscillation of the active valves by a centrifugal governing device 54 and a governor-collar 40, which revolves with the shaft 3 and is shifted endwise upon it by the action of the governor- 40 weights through connecting-arms 55, as shown in Fig. 6, to which I am now referring. Upon the surface of this collar and suitably insulated therefrom is a contact-plate 44, disposed at a slight spiral, which ends abruptly at the 45 shoulders 56 and 57, the latter of which has a lead of the former slightly in excess of the width of the brushes 39 and 43 to avoid the chance of short-circuiting through plate 44, so that, considering the collar to revolve according 50 to the arrow, the brush 43 will have passed off the shoulder 56 onto the insulation with which the collar is surfaced above and below the plate before brush 39 will have contacted with shoulder 57. The valve-opening 55 brushes 39, 39^a, and 39^b are equidistant, respectively, from the valve-closing brushes 43, 43^a, and 43^b, each pair being spaced a distance slightly greater than the width of the plate 44, which is uniform throughout except 60 between the shoulders 56 and 57, to give a clearance which will prevent short-circuiting. Each of the brushes 43 is spaced from the other a distance corresponding with the elevation of the spiral of the sleeve 44, so 65 that only one of them at a time can intermit-

tently engage said sleeve to effect an oscillatory movement of the valve or valves it controls, and the same is true of brushes 39. Now, assuming the governor and its collar or commutator 40 to be revolving, sensitive to 70 the turbine's speed, the brushes 39 and 43 will be alternately in contact with the sleeve 44 by virtue of its spirally-tapered edges once during each complete revolution of the sleeve, and since when they contact with said sleeve 75 they energize the motor-armature to open and close the valve it is obvious that the valve's movements depend upon the length of time each brush remains in contact with the sleeve. This is the basis of my oscillatory regulation, 80 because as the load of the turbine diminishes its speed will increase and the sleeve will rise, thus maintaining contact for a greater portion of its revolution with the valve-closing brush 43, whereas when the load increases the sleeve 85 will move in the opposite direction and maintain a longer contact with the valve-opening brush 39. By these means the valve or valves controlled by the brushes 39 and 43 will be oscillated sensitive to the turbine speed and 90 will regulate the efficiency of the turbine in direct proportion to the load by varying the duration of the blasts of elastic fluid which are admitted to the nozzles while the valve-opening brush makes contact. Since the valve 95 opens fully each time the armature-coils are energized through brush 39, there will be no wiredrawing or throttling of the nozzles and the fluid-pressure will always be admitted, so that its volume and the velocity into which it 100 is largely converted in the nozzles remain uniform. In the diagrammatic view Fig. 11, illustrating the action of a valve under an increasing load, the line *c* represents the valve 105 passively closed, while *o* represents it passively open. Intermediate these points the length of the vertical lines indicates the volume and velocity and their distance apart the beginning and ending of the pulsations. The points *r r* in the line above this figure denote 110 the series of complete revolutions of the commutator 40, while the upper horizontal lines of increasing length denote the increasing portions of succeeding revolutions, during 115 which the valve is maintained open until it becomes passively open, whereupon the oscillations of the valve next above commences. This method of regulating the motor - fluid supply to the turbine and the controller means for governing the operation of the supply-valves form the subject-matter of pending applications and are not broadly claimed 120 herein.

In adapting my governing mechanism to turbines of large powers in which a continuous row of nozzles are employed extending entirely around the turbine and having each a valve and a motor therefor, as shown in Figs. 1 and 2, the governor-commutator 40 is mounted on a horizontal shaft 58 and longitu- 130

dinarily movable thereon by the lever 58^a, pivotally mounted in a vertical extension 59 of the turbine-frame and connected to the slip-collar 60 on the vertically-movable governor-collar 61 and a similar slip-collar 62 on the commutator near the inner end thereof. The vertical movement of the collar 61 thus serves to shift the commutator on shaft 58, to which it is loosely keyed by feather 63, the shaft being rotated by the main shaft 3 through the bevel-gears 64 and 65. Because of the large number of valve-motors it is desirable to provide the commutator with two or more sleeves 44, which have similarly-shaped strips of insulation interposed between them, so that the brushes may be grouped in banks of twelve for each sleeve, as shown in Fig. 1, when each corresponding pair of valve opening and closing brushes operates four of the forty-eight motors shown simultaneously. These motors are oppositely disposed, so that the action of their nozzles balance each other, and any desired number may thus be grouped together. In the case of Fig. 2 I have shown forty-two nozzles with the valve-operating motors therefor connected in pairs and controlled by three banks of brushes of fourteen each and three contact-sleeves 44 on the commutator. Each bank of brushes is distinct from the others and comprises six valve-opening brushes 39 and six corresponding valve-closing brushes 43, over which the contact-sleeve 44 is moved by the governor to oscillate the valves controlled by each pair of brushes, while the rest are either open or closed, according to the load. With each bank of brushes, as also in Fig. 6, it is evident that one valve-opening brush and its corresponding valve-closing brush will always be in intermittent engagement with the tapering edges of its contact-sleeve, while the rest of the brushes will be in constant contact with either the sleeve or the adjoining strip of insulation, so that their valves are passively open or closed. If we take the commutator near the lowest point of its throw, as shown in Figs. 1 and 2, in dotted lines, Fig. 6, and for convenience describing the action of the bank of brushes in the latter figure as illustrative of the others, we find brushes 39^a and 39^b will be in constant engagement with the sleeve, thus maintaining their respective valves open, while brushes 39^b and 43^b (or 39^c and 43^c in Fig. 1) will be on the taper edges of the sleeve, and therefore regulating the turbine by oscillating their valves. If the reduction of load be gradual, the commutator will move up slowly until the sleeve contacts with brushes 39^a and 43^a, when the valve of brush 39^b will be maintained closed. This same movement will continue until all the valves controlled by brushes 39^a and 39^b are closed and brush 39 is active. At the extremes of the collar's travel, which occurs when the load is either full on or off, the plate 44 is so shifted that it

engages all of the valve-opening brushes to hold their nozzles constantly open or all the valve-closing brushes to hold their nozzles constantly closed. If, on the other hand, there should be large and sudden variations in the load, the governor will sweep the sleeve back and forth over the bank of brushes so rapidly that the oscillatory regulation derived from the tapering edges of the sleeve is lost, and the nozzles are thrown open or closed to effect the regulation. Under such circumstances the commutator shown in Fig. 3 may be used, and it is found that the slight pumping action of the turbine during a steady load will in a way compensate for the oscillatory control derived from the tapering sleeves by causing a slight oscillation of the commutator itself. In these figures the field-wires 35 are connected to a common wire 66 and through it to the ground P.

Having thus described my invention, what I claim as new, and desire to secure by Letters Patent, is—

1. In a turbine, the combination of a number of nozzles, valves for said nozzles, rotary motors transmitting motion to said valves to actuate them, and a governor for controlling the operation of said motors to throw said valves into and out of service.
2. In an elastic-fluid turbine, a rotating element, a fluid-supply passage, a series of partitions therein which direct the fluid in streams against said rotating element, a rotary valve controlling the admission of fluid to each passage formed by said partitions, and a governor controlling the operation of said valves.
3. In an elastic-fluid turbine having a nozzle, a rotary valve having only open and closed positions controlling the admission of fluid-pressure to said nozzle, and governor-controlled means to operate said valve.
4. In an elastic-fluid turbine having one or more nozzles, a governor-controlled electrically-operated rotary valve for each nozzle controlling the admission of fluid-pressure thereto.
5. In an elastic-fluid turbine, a plurality of nozzles, a rotary valve for each nozzle located in the throat thereof, and electromagnetic means suitably governed for rotating each valve.
6. In an elastic-fluid turbine, an expansion-passage and a valve in the throat thereof that forms when open a symmetrically-curved intermediate part of each side of the contracted portion of said passage.
7. In an elastic-fluid turbine, a series of nozzles, governor-controlled rotary valves controlling the admission of fluid-pressure thereto and substantially radially disposed about said turbine.
8. In an elastic-fluid turbine, a circular series of nozzles, rotary valves controlling the admission of fluid-pressure thereto and having

stems disposed substantially radially about said turbine, and governor-controlled operating means connected to said stems.

9. In an elastic-fluid turbine, a nozzle, a valve which has only open and closed positions to control the admission of fluid-pressure thereto and which is balanced when open, and means sensitive to the speed of the turbine for operating said valve.

10. In an elastic-fluid turbine, an expansion-nozzle, a valve having only open and closed positions which controls the admission of fluid-pressure thereto and when open is balanced and when closed is held firmly to its seat by the unbalanced pressure, and means sensitive to the speed of the turbine for operating said valve.

11. In an elastic-fluid turbine, a governing or regulating mechanism for a pulsatory feed whereby impulses or blasts of uniform volume but varying in duration are admitted by a rotary valve, suitably controlled, to a nozzle-passage.

12. In an elastic-fluid turbine, a nozzle, a governing or regulating mechanism for controlling the admission of fluid-pressure to said nozzle by oscillating a rotary valve having the periods of rest at each end of its travel governed sensitive to the turbine's load.

13. In an elastic-fluid turbine a governing mechanism comprising electric magnetic means for controlling the admission of fluid-pressure to said turbine and governor-actuated tapered controller devices governing the action of said means.

14. In an elastic-fluid turbine, a rotating element, a series of nozzles, valves therefor, electromagnetic means controlling said valves, a governing mechanism sensitive to the speed of the turbine, which moves a plurality of tapered controller devices.

15. A governing mechanism for elastic-

fluid turbines, comprising a plurality of valves controlling the flow of motive fluid, electric means actuating said valves, and governor- 45 actuated spirally-tapered controller devices for said means suitably spaced apart.

16. In an elastic-fluid turbine, a rotating element, nozzles delivering fluid-pressure thereto, rotary valves therefor and electro- 50 magnetic means for operating said valves in combination with a governing mechanism comprising a generator having its terminals suitably grounded, brushes controlling the circuits to said operating means, and a controller device which is engaged by one or more of said brushes and serves to close their circuit to said generator.

17. In an elastic-fluid turbine, a rotating element, a supply-passage delivering the fluid 60 directly to said rotating element, and a number of slanting transverse partitions disposed only in the delivery portion of said passage and acting to divide the fluid into a plurality of expanding streams, and means disposed 65 within the delivery portion of said passage to control said streams independently.

18. In an elastic-fluid turbine, a plurality of nozzles, valves therefor, and mechanism sensitive to the speed of the turbine for controlling 70 said valves independently in groups and synchronously pulsating the corresponding valves in each group.

19. In an elastic-fluid turbine, a plurality of nozzles, valves therefor, operating means for 75 said valves arranged in groups, and a tapering governor-controller device for each group.

In testimony whereof I affix my signature in presence of two witnesses.

JAMES WILKINSON.
